UNITED STATES PATENT OFFICE.

WINSLOW W. CHASE, OF WASHINGTON, DISTRICT OF COLUMBIA.

DESIGN FOR A THERAPEUTIC VACUUM APPARATUS.

55,452.

Specification for Design.

Patented June 15, 1920.

Application filed November 8, 1917. Serial No. 200,983. Term of patent 7 years.

To all whom it may concern:

Be it known that I, WINSLOW W. CHASE, a citizen of the United States, residing at Washington, in the District of Columbia, have invented a new, original, and ornamental Design for a Therapeutic Vacuum Apparatus, of which the following is a specification, reference being had to the accompanying drawing, forming part thereof.

Figure 1 is a perspective view of a therapeutic vacuum apparatus, showing my new design.

Fig. 2 is a side elevation of the same.

I claim:

The ornamental design for a therapeutic vacuum apparatus, as shown.

WINSLOW W. CHASE.
